(57) **CLAIM**

The ornamental design for a solar plant drip irrigator, as shown and described.

DESCRIPTION

FIG. 1 is a perspective view of a solar plant drip irrigator showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the solar plant drip irrigator.

The broken lines in the drawings depict portions of the solar plant drip irrigator that form no part of the claimed design.
